SEWING MACHINE

Fred Ricks, Leicester, England, assignor to United Shoe Machinery Corporation, Paterson, N. J., a corporation of New Jersey

Application November 10, 1932, Serial No. 642,051
In Great Britain December 10, 1931.

6 Claims. (Cl. 112—35)

This invention relates to sewing machines and is particularly, but by no means exclusively, concerned with boot or shoe inseam sewing machines for use in sewing together the welt, upper and insole of a welt shoe or the upper and sole of a turn shoe.

An example of this class of machine is the well-known Goodyear welt and turn shoe sewing machine which is disclosed in U. S. Patent to Eppler, No. 1,108,560 dated August 28, 1914 and which may be provided with continuous work feed mechanism such as is disclosed in the U. S. Patent to Topham No. 1,289,314, dated December 31, 1918.

Machines of this class have a curved hook needle, a looper, a thread finger and take-up which cooperate in forming a chain stitch seam. During the formation of each stitch the thread finger is swung rearwardly of the machine and draws a bight of the thread which extends between the work and the looper, the needle then having penetrated the work and being in position to have the thread laid in its hook by the looper. After the looper has laid the thread in the hook of the needle and as the needle moves back to draw a loop of thread through the work, the thread finger swings forwardly and gives up thread to one side of the needle while the thread at the other side of the needle is drawn through the looper.

In machines as heretofore constructed a difficulty has been sometimes experienced in manipulating the shoe while it is being operated upon so as to present successive portions of the parts to be sewn together properly to the sewing devices. This difficulty has been due to the fact that the thread finger as it swings back may sometimes hit against the upstanding channel lip or lips of the insole and tend to push the shoe downwardly away from the sewing devices. This difficulty is found to be greater when sewing round the toe of a shoe than when sewing along the side because the channel lip or lips and the upper materials are more compact than at the sides and offer greater resistance to the movement of the thread finger and also because when sewing round the toe of a shoe the thread finger is at times, owing to the positioning of the shoe, swinging in a direction along the channel lips instead of across them, and thus tends to prevent proper presentation of the shoe to the sewing devices.

The difficulty above referred to has been present in machines in which the shoe has been fed intermittently, but in such machines can be

overcome to a large extent, if not indeed wholly, by careful manipulation of the shoe. In machines in which the shoe is fed intermittently the turning at the toe or manipulating of the shoe is intended to be done by the operator while the shoe is being fed and therefore while the needle is out of the work and it will be apparent that the movement of the shoe during its feed indicates to the operator the time in each cycle during which the shoe can best be manipulated. When, however, the shoe is being fed continuously or substantially so, as in a machine fitted with continuous feed mechanism, there is nothing to indicate to the operator when the needle is out of the work and careful manipulation of the shoe to overcome the difficulty above referred to is rendered more difficult.

One of the several objects of the present invention is to overcome the aforementioned difficulty and this object may be achieved in one preferred way, according to the present invention, which will be hereinafter described with reference to the accompanying drawings.

In the drawings Fig. 1 illustrates, in side elevation, a portion of a welt shoe sewing machine embodying the present invention, which sewing machine is of the general construction described in the patents above referred to, and more particularly in the patent to Topham; Fig. 2 is a view in side elevation on a somewhat larger scale than Fig. 1 of part of a welt shoe sewing machine embodying the present invention, which machine is of the general construction described in the patents above referred to, and more particularly in the patent to Eppler; Fig. 3 is a view in front elevation partly in section of a portion of the mechanism illustrated in Fig. 2; Figs. 4 to 7 inclusive illustrate diagrammatically an arrangement of channel guide, back rest, needle, looper, and thread finger with the parts in some of the different relative positions they occupy during the formation of a stitch in the machines shown in Figs. 1, 2, and 3; Fig. 8 shows in plan the toe end of a welt shoe and the relative position of the parts illustrated in Figs. 4 to 7 at one point in the formation of a stitch, and Fig. 9 illustrates on an enlarged scale a portion of the arrangement for supporting and actuating the looper.

In the drawings 1 is the channel guide, 2 the back rest, 3 the needle, 4 the looper, and 5 the thread finger of the said welt sewing machine.

In Figure 4 the parts are shown in the relative positions they occupy when the machine comes to rest and a shoe which has been sewn can be re-

moved and a fresh shoe presented to the machine. In Figure 5 the thread finger 5 has swung back to take a bight of the thread which extends between the looper 4 and the work and the needle 5 has passed through the work.

In Figure 6 the needle and thread finger are in the same positions as in Figure 5 but the looper 4 has moved down and is part way round the point of the needle in its looping movement.

10 In Figure 7 the needle and thread finger are in the same positions as in Figures 5 and 6 and the looper 4 is shown as having moved round the point of the needle and laid the thread in the barb.

15 In Figure 8 the needle 3, thread finger 5 and looper 4 are shown in the same relative positions as in Figure 6 and this figure illustrates the movement of the thread finger along the channel lip or lips when sewing round the toe of a shoe as hereinbefore referred to.

20 It will be observed from Figures 4 and 7 of the drawings by those familiar with this class of machine as in general use that the thread finger 5 performs its swinging movement well above the channel lips and margin of the upper, that is to say, in an unusually elevated position so that it cannot encounter any part of the shoe properly presented to the machine. To allow the thread finger to take its bight of thread, the looper 4 has also been caused to move into an unusually elevated position so that the thread finger and looper at the time in the cycle of the machine when the thread finger takes its bight of thread are substantially in the same relative positions as heretofore. To enable the looper 4, however, to lay 30 the thread in the barb of the customary needle coming in each cycle to the conventional position, it is caused to move towards the needle in the direction of the length of the needle or dip by suitable modification of its operating mechanism as hereinafter described from its raised position so that it can perform its looping operation and is then raised again so that the thread finger can take its bight of thread during the next cycle. By causing the thread finger and looper to cooperate in a raised position and causing the looper to have an up and down movement in the direction of the length of the needle to effect the laying of the thread in the barb of the needle, ample clearance is provided between the work and the 40 thread finger at all times so that the shoe can be freely manipulated when the needle is out of the work without interference by the thread finger.

45 In the operating mechanism of the looper hereinbefore referred to and illustrated in Figures 1, 2, and 3 of the drawings the looper 4 is actuated in its movement across and forwardly and rearwardly of the machine to lay the thread in the barb of the needle by mechanism similar to that shown in the Eppler patent, but the looper 4 instead of being fixed in the arm 6 is formed on a bar 7 which is slidingly mounted in a guideway formed in the lower end of the arm 6, which guideway is substantially parallel when viewed from the front and side of the machine to the 50 arm.

55 The bar 7 has extending laterally from it a stud 8 having a ball end which makes a universal connection with the lower end of an upwardly and forwardly extending link 9, the upper end of 60 which, in a welt shoe sewing machine in which the work is fed continuously as in the machine described in the Topham patent, and shown in Fig. 1 of the drawings, has a universal connection with the cam arm 10 which effects the swinging of the channel guide towards and from the chan-

nel. In a welt sewing machine in which the work is fed step by step and in which the channel guide as it is moved towards the work moves along a line approaching the needle and inclined to the direction of feed, as described in the Eppler patent, the upper end of the link 9 is, as shown in Figs. 2 and 3 of the drawings connected by a universal joint to an arm 11. The arm 11 is pivoted on the head of a shaft 12, corresponding to the shaft referred to as 75 in the Eppler patent, and is secured by a screw 13 to an arm 14 of a cam lever 15 which is pivoted on a sleeve 16 in which the shaft 12 is rotatably mounted and which sleeve is secured in a bracket 17 fixed on the machine head. The lever 15 carries a cam roll 18 which enters a cam groove in a cam ring 19 secured to the cam block 20, in which is the usual cam groove by which the channel guide is moved towards and from the work. The cam groove in the cam ring 19 is similar to the groove which actuates the cam lever referred to as 28 in the Topham patent, which latter cam imparts to the channel guide a movement towards and from the work support. In this way the looper is given a similar up and down movement in a welt sewing machine having a continuous work feed or in a machine having a step by step feed.

5 In Figure 3 the cam arm which moves the channel guide towards and from the work is shown at 21. The cam arm 21 is secured at one end to the shaft 12 and at the other end carries a cam roll 22 on a stud 23 fixed in the arm, which stud passes through the cam ring 19. By means of the cam arm referred to as 28 in the Topham patent or the cam arm 15 and link 9, the looper 4 is caused to dip during each cycle of the machine from its unusually elevated position so that it can, by means of the mechanism shown in the Eppler patent lay the thread in the barb of the needle and is then by the cam arm and link raised again to its elevated position. Owing to its connection to the cam arm, the dipping of the looper occurs at the same time as the moving of the channel guideway from the channel to allow of its return feed movement and the raising of the looper occurs when the channel guide is moved back into engagement with the channel. At the same time that the looper is caused to dip from its elevated position it is also swung to the right (viewing the machine from the front) and moved forwardly by the mechanism shown in the Eppler patent to move it from the left hand side of the needle, where the thread finger takes its bight of thread to the right hand side of the needle and remains in this dipped position while its lower end is moved completely round the needle by the latter mechanism to lay the thread in the barb of the needle. As the needle moves back to draw its loop of thread through the work, the looper is swung to the left by the last mentioned mechanism and at the same time is raised from its dipped position by the link and cam arm to return it to its position at the left of the needle where the thread finger can again take its bight of thread.

65 The nature and object of the invention having been explained, and mechanism in which it may be embodied having been specifically described what is claimed is:

1. An inseam shoe sewing machine having, in combination, stitch forming devices including a curved hook needle, a looper and a thread finger arranged to give up thread as the needle withdraws from the work and to move in an elevated path at a distance from the work and from the 70

- needle barb while the needle is through the work sufficient to clear the channel lip and upper margin of the shoe, means for actuating the looper to carry the thread into the path of movement 5 of the thread finger and around the needle, and means for moving the looper during each cycle of operations towards the needle in the direction of the length of the needle to cause the thread first to be engaged by the thread finger and there- 10 after to be engaged in the needle barb.
2. An inseam shoe sewing machine having, in combination, stitch forming devices including a curved hook needle, a looper and a thread finger arranged to give up thread as the needle with- 15 draws from the work and to move back and forth across the channel lip and upper margin of the shoe in an elevated path at a distance from the work and from the needle barb while the needle is through the work sufficient to clear the 20 channel lip and upper margin of the shoe, means for actuating the looper to carry the thread into the path of movement of the thread finger and around the needle, and means for moving the looper during each cycle of operations upwardly 25 from the work to cause the thread to be engaged by the thread finger at the proper time in each cycle of operations for the next succeeding stitch.
3. An inseam shoe sewing machine having, in combination, stitch forming devices including a curved hook needle and a looper, a back rest, a channel guide, means for actuating the channel guide towards and from the back rest, means for actuating the looper during each cycle of operation of the machine to carry the thread around 30 the needle, and connections between the channel guide actuating means and the looper for moving the looper towards and from the needle in the direction of the length of the needle.
4. An inseam shoe sewing machine having, in combination, stitch forming devices including a curved hook needle, a looper, a thread finger, a 35 back rest, and a channel guide, means for actuating the channel guide towards and from the back rest, means for actuating the looper during each cycle of operation of the machine to carry the thread into the path of movement of the thread finger and around the needle, and connections between the channel guide actuating means and the looper for moving the looper towards the needle in the direction of the length of the needle after the thread is engaged by the thread finger. 10
5. An inseam shoe sewing machine having, in combination, stitch forming devices including a curved hook needle and a looper, a back rest, a channel guide, means for actuating the channel guide towards and from the back rest, a slide on 15 which the looper is supported, a looper actuating member having a guideway for the slide extending in approximately the direction of the length of the needle, means for moving the actuating member to carry the thread extending 20 from the looper around the needle, and connections between the slide and the channel guide actuating means for reciprocating the slide to shift the looper towards and from the position where it may lay the thread within the needle 25 barb.
6. An inseam shoe sewing machine having, in combination, stitch forming devices including a curved hook needle, a looper and a thread finger, a slide on which the looper is supported, a looper 30 actuating member having a guideway for the slide extending in approximately the direction of the length of the needle, means for moving the actuating member to carry the thread extending from the looper into the path of movement of the 35 thread finger and around the needle, and means for actuating the slide to shift the looper from one position in which the thread finger receives the thread into another position in which the thread is laid within the needle barb. 40

FRED RICKS.
